UNITED STATES PATENT OFFICE

2,406,278

CLEANER

Thomas C. Worth, Market Harborough, England

Application July 12, 1943, Serial No. 494,295

2 Claims. (Cl. 183—8)

1

This invention relates to an air or gas cleaner, and it has for one object to provide means for separating dust, dirt or other solid matter from a moving stream or column of air or gas.

It has for another object to provide a means for carrying out in a single apparatus two stages of separation, in one of which the heavier or larger particles are removed, and in the other of which the smaller or lighter particles are removed.

Another object is to provide in a single, compact apparatus, means for accomplishing dry separation and fluid separation in a single, continuous process.

Another object is to provide an apparatus of the type indicated formed of a plurality of readily separable parts to permit effective and convenient cleaning.

Other objects will appear from time to time throughout the specification and claims.

This invention is illustrated more or less diagrammatically in the accompanying drawing, wherein:

Figure 1 is a vertical section through one form of the device;

Figure 2 is a transverse section taken at line 2—2 of Figure 1; and

Figure 3 is an elevational detail showing one form of a separable attaching means.

Like parts are indicated by like characters throughout the specification and the drawing.

In the particular form here shown, the device comprises a housing which is, in effect, formed by three main and preferably separable parts. There is thus an upper housing section 1, which may be cylindrical in cross section, which is closed by a member 2 which may be permanently secured in place or, if desired, may be removable. The member 1 is provided with a perforation or opening 3 in which an outlet connection member 4 is positioned.

Within the housing 1 a mass of filter material 5 is positioned. It is convenient to hold this material in place by an upper member which may comprise an annular portion 6 and a plurality of branches 7 which may meet at the center, as at 8. In general, the member formed by these parts is shaped to provide many openings, but is of such size and shape, and the openings are of such size and shape, as to prevent the filter material from being carried away in the moving stream of air or gas.

The filter mass is supported and positioned from below by a member which may comprise an annular member 9 and arms or branches 10 which may be joined centrally, as at 11. The arrangement and purpose of the lower filter supporting means is generally the same as the upper member just described above. The annular portions 6 and 9 may be welded to the housing or, if

2

desired, may be removably secured to the housing.

An intermediate housing section 12 is, in effect, cuplike. It comprises a generally cylindrical portion 14 which fits, as at 13, about the lower portion 11 of the housing section 1. The housing section 1 may be provided with an outwardly extending bead or flange 15, against which the upper edge 16 of the housing section 12 abuts when the parts 10 are assembled together. One convenient means for securing the two housing sections together comprises bayonet locks which are formed by slots 17 in the section 12 which embrace pins 18 in the section 1. Other attaching means could, of course, be substituted for these.

The housing section 12 is provided with a bottom portion 19 which is preferably integral with the side portion 12 and which is also preferably integral with a central tubular inlet member 20. Preferably the cup portion formed by the members 12, 19 and 20 is rounded, as at 21 and 22. The upwardly extending inlet member 20 may be provided with a flange or bead 23. Positioned within the portion 12 and engaging the inner face of the member 20 is a baffle 24 which is annular in plan and is preferably curved or concave and upwardly facing. Its inner edge lies against and is preferably secured to the upper end of the member 20, as at 25, and it may be provided with openings 26 adjacent which are positioned outwardly extending members 27. It may also be provided with openings 28 adjacent which are positioned inwardly extending members 29. This baffle may conveniently be welded or otherwise permanently secured to the member 20. Positioned above and overlying the upper end of the member 20 is an inwardly directed baffle 30. It may be secured to the upper end of the member 20 by arms 31 which are secured to that member and to the baffle. As shown, the outer edge 32 of the baffle 30 projects into the area bounded by the baffle 24, and the lower edge 32 of the baffle 30 is below the upper edges of the baffle 24 and below the upper edge of the member 20. The cup member ordinarily contains a quantity of oil or other liquid and preferably that liquid stands at a level somewhat above the lower edge 32 of the baffle 30, although considerable variation in the oil level may occur without destroying the effectiveness of the device.

A third housing section is positioned removably below the section 12 and may be held in place by a spring bail 33 which is preferably provided with a roller or other anti-friction device 34, the bail being pivoted in ears 35 which are integral with a band 36, which is itself positioned about and secured to the housing section 12. The lower section includes a shell or housing portion 37 which at its upper edge abuts against a portion 60 of the member 12, preferably the bottom portion

19, and it is provided with a plurality of openings 38 which are formed by outwardly projecting tongues 39. The effect of this construction is to give entering air a whirling motion. One or more slots or openings 40 are formed in the shell 37 and adjacent each of these there is preferably formed an outwardly projecting lip or vane 41 which tends to scoop off solid matter which comes into contact with the inner surface of the member 37 or approaches that surface. This solid 10 matter is directed to the openings 40 and passes through them into a space which is defined partly by the member 37 and partly by a shell 42. This shell at its upper edge 43 is in sealing contact with a flange or collar 44 which is secured to the shell 37, as at 45, and the space enclosed between the members 37 and 42 thus forms a receptacle into which solid matter deposited from the air as it whirls about within the shell 37 is collected and retained.

Although I have shown an operative form of my invention, it will be recognized that many changes in the form, shape, and arrangement of parts can be made without departing from the spirit of the invention, and my showing is, therefore, to be taken as, in a sense, diagrammatic. In particular, the structural details may be widely varied. The means for holding the parts separably together might be of almost any type. The relative proportions of the baffles within the oil bath portion 12 might be widely varied. The number of openings in the baffle 24 and their particular shape and disposition might be widely varied. Similarly, the number of openings in the member 37 and their positioning in that member might be widely varied.

The use and operation of this invention are as follows:

The invention will ordinarily be associated with an internal combustion engine as a means for cleaning the air which passes to the engine, although it may be used in many other associations in which it is necessary or desirable to remove solid matter from a moving column of air or gas. If it be assumed that the cleaner is to be used in connection with an engine, the member 4 will be connected with the carburetor or will otherwise be connected to carry clean air to the point of use. As the engine commences to operate, suction occurs and air is drawn through the cleaner, entering the openings 38 and being given a whirling action. The air thus circulates or whirls about the space within the chamber 37, and the heavier matter tends to move outwardly and hence approach or come in contact with the inner surface of the member 37. Such heavier matter passes through the opening or openings 40 and may be assisted in this movement by the scooping action of the members 41 if they are present. Once solid matter has passed through the wall of the shell 37, it is entrapped and remains within the space defined by that member and the member 42.

The relatively cleaner air now moves upwardly through the member 20 and is directed downwardly by the member 30 toward the oil or other liquid which is present. The air then moves upwardly again beyond the lower edge 32 of the baffle 30 to and through the filter mass 5. The liquid within the cup portion 12 is to a greater or less degree carried upwardly by the passage of the air or gas, and to a greater or less degree saturates the filter mass, so that the relatively small passages through which the air or gas must move in passing through the filter mass are lined 75

with cleaning liquid, and the solid matter is further entrapped in this liquid and removed from the column of gas. The liquid itself tends to flow downwardly again into the cup and carry with it this solid matter.

The cleaned air finally emerges from the filter mass and passes outwardly through the connection 4 to the point of use.

I claim:

1. In an air cleaner built up from vertically aligned nested cups, a bottom cup adapted to receive dust, a dry cleaner cup closing the top of the bottom cup and including a bottom portion extending into the bottom cup and having dust discharge apertures associated with dust directing vanes therein and a side portion extending above the bottom cup and having air inlet apertures, a liquid containing cup closing the top of the dry cleaner cup and having an axial air discharge duct extending upwardly above the level of the liquid in said cup and adapted to serve as an air discharge outlet for the air entering the dry cleaner cup, an arcuate mushroom baffle overlying the upper end of said axial duct, adapted to direct air downwardly toward the liquid in said liquid containing cup, an upwardly convex circumferential baffle provided, at its bottom, with baffled openings and aligned with the path of flow of air from said mushroom baffle, extending below the liquid level in said liquid containing cup and having an outer discharge edge spaced radially outwardly from the outer edge of the mushroom baffle, and a container positioned above and closing the top of the liquid containing cup, having a cleaned air discharge duct extending therefrom and having an air pervious filter mass therein in the line of delivery of air from said liquid containing cup.

2. In an air cleaner, a centrifugal separator container having a generally cylindrical upper portion and a cup-shaped lower portion, said upper portion having outwardly extending inlet scoops spaced circumferentially thereabout and adapted to impart to the inflowing air a path conforming generally to the inner face of said upper portion, said lower portion having inwardly extending dust scoops, extending into the path of flow of the air to be cleaned, a dust receiving housing surrounding the lower portion of the separator container and defining a dust-receiving space in communication with said dust scoops, and a discharge outlet duct extending upwardly from said upper portion of the separator container, a liquid container positioned above and partly closing the top of said centrifugal separator container and having a central air discharge duct extending to a level above the level of liquid in said container, an inverted arcuate mushroom shaped baffle adapted to direct the air which flows upwardly through said discharge duct downwardly toward and against the liquid in said container, an additional cleaning housing closing the top of said liquid container, an air pervious filter mass positioned therein, and an additional upwardly convex baffle positioned in said liquid container and surrounding said air discharge duct, said additional baffle having, in its bottom, baffled openings and being of substantially greater diameter than the diameter of said inverted baffle, whereby it is adapted to direct air upwardly toward the bottom of said air pervious filter mass, and means for removably securing said containers in nested relationship.
